PROCESS FOR CONVERTING PETROLEUM OIL

Original Filed Dec. 1, 1922

UNITED STATES PATENT OFFICE

GUSTAV EGLOFF AND JACQUE C. MORRELL, OF CHICAGO, ILLINOIS, ASSIGNORS TO UNIVERSAL OIL PRODUCTS COMPANY, OF CHICAGO, ILLINOIS, A CORPORATION OF SOUTH DAKOTA

PROCESS FOR CONVERTING PETROLEUM OIL

Application filed December 1, 1922, Serial No. 604,163. Renewed February 5, 1929.

This invention relates to improvements in a process and apparatus for converting petroleum oil and refers more particularly to the conversion of hydrocarbon products from oils of a relatively high boiling point to oils of a lower boiling point such as gasoline and the like.

Among the objects of the invention are to provide a process in which after cracking the oil under pressure and subjecting it to a refluxing and condensing action the uncondensed gases are re-treated to extract therefrom light hydrocarbons which may be contained therein, to provide a process in which these gases are re-treated to produce light hydrocarbons in separate stages which may be alternately isolated from the system whereby more continuous operation is effected. The single figure is a diagrammatic side elevation-
al view of the apparatus.

Referring to the drawings and explaining the drawings in connection with the flow of the oil there is introduced through the pipe 1 controlled by a valve 2, a raw oil charge from any convenient source. This oil flows through the line 3 and is charged by means of the pump 4 through the heating coils 5 mounted in a furnace 6. This furnace may be of any convenient type and is preferably heated by means of gas burners 7. The oil after being circulated therethrough is raised to a conversion temperature and in this condition passes through the transfer line 8 regulated by a valve 9 to the conversion or vaporizing chamber 10. This chamber preferably consists of an enlarged tank or receptacle which may be heavily insulated to prevent loss of heat by radiation. Try-cocks 11 are tapped in at different levels in order that the operators may ascertain the level of the oil at all times. Separate residuum lines 12 controlled by valves 13 furnish a means for withdrawing unvaporized oil constituents from the vaporizing stage. The evolved vapors and gases rise through the line 14 controlled by a valve 15 and are introduced to the bottom of the dephlegmating or refluxing column 16. The vapors rising through the refluxing column are interrupted by a series of perforated pans 17 in which the condensate

separated from the vapors may collect, dropping back to the bottom of the refluxing column and there being collected in the dephlegmator leg 18 and returned to the charging line through the pipe 19 controlled by a valve 20. If the reflux condensate becomes excessive, portions may be drawn off through a line 21 controlled by a valve 22 and directed to any convenient storage. The vapors passing off from the top of the dephlegmator pass through the line 23 regulated by a valve 24 to the condenser coil 25 positioned in the water condenser box 26. The liquid distillate condensed therein flows down through the line 27 controlled by a valve 28 and is collected in the receiving tank 29. This latter tank is equipped with a liquid level gauge 30, pressure gauge 31, a liquid draw-off line 32 controlled by a valve 33 and a gas draw-off line 34 controlled by a valve 35. The liquid draw-off line 32 communicates with a separating tank 36 to which the liquid distillate is directed and permitted to collect under a lower pressure, which is controlled by the valve 33. The tank is equipped with a liquid level gauge 37, a liquid draw-off line 38 regulated by a valve 39 and a gas draw-off line 40 in which is interposed a throttle valve 41. The release in pressure on this tank may be any pressure ranging from a pressure slightly below the pressure maintained upon the system down to atmospheric, or a vacuum pressure may be imposed by means of the vacuum pump 42. With this lowering of pressure upon the distillate there is an increased evolution of gaseous vapors which are drawn off through the line 40 and directed through the pump 42 into the line 43. This line has communication with the gas line 34 tapped into the top of the receiving tank 29. A by-pass line 44 regulated by a valve 45 furnishes a means for by-passing the gases from the receiving tank to the suction side of the vacuum pump. The gases from the separating tank 36 and receiving tank 29 are thus charged through the line 43 into either of the columns 46 or 47. These columns are preferably cylindrical in form, having a zone of checker work brick as shown at 48 in their lower portions. Above these bricked por-

- tions is a broken up and absorbent agent such as charcoal shown at 49. The columns are connected into the system so that either may be isolated therefrom while the other is being operated as a part of the system, that is, the gases flowing through the pipe 43 may be introduced to the column 46 through the secondary line 50 and perforated rose 51 by opening the valve 52. On the other hand by closing the valve 52 the gases will pass on and may be introduced to the column 47 by opening the valve 53 interposed in the line 54, the upper end of which terminates in a rose 55 identical in construction to that shown at 51 in the column 46. As an alternative and in case both columns are to be cut out of the system, the gases may be directed through the line 56 by closing the valves 52 and 53 and opening the valve 57.
- 20 Assuming the column 47 is cut out of the system and the gases are directed into the column 46 under such conditions the valves 53 and 57 will be closed and the valve 52 opened.
- 25 The gases containing light hydrocarbon which remained uncondensed after condensation in the water condenser coil 25 will rise through the checker work brick and percolate through the broken up absorbent agent contained thereabove. The light hydrocarbons separable from these gaseous vapors will be both absorbed and adsorbed while the incondensable gas will pass off from the top of the column through the lines 58 and 59 controlled by valves 60 and 61 respectively to the gasometer 62. When the absorbent agent in the column has become saturated or substantially so the valves 52 and 60 may be closed and the valves 53 and 63 opened, the latter valve 63 being in the upper gas draw-off line 64 by means of which uncondensed gas from the column 47 is withdrawn.
- 30 In the meantime a portion of the expended combustion gases are withdrawn from the stack 65 and returned through the line 66 controlled by valve 67 to the pump 68 by means of which they are caused to pass through a coil 69 positioned in the furnace 6, thus these gases are heated to a high temperature and directed through the insulated line 70 controlled by a valve 71 to the header 72 which is connected to the line 70 by a secondary connection 73 and valve 74 is interposed in this latter line.
- 35 After the column 46 has been cut out of the system these heated gases are returned and injected into the column through a pipe 75 controlled by a valve 76. The temperature of these gases is sufficient to readily drive off the lighter hydrocarbons which were taken up by the broken fragmentary material shown at 49. These light hydrocarbons in a vaporous condition pass off through the line 77 regulated by a valve 78 and into the pipe 79 communicating with the water condenser

coil 80 where they are reduced to liquid form and collected in the receiving tank 81 communicating with the discharge end of the condenser coil. The receiving tank 81 is equipped with a liquid level gauge 82, pressure gauge 83 and liquid draw-off valve 84 and a pressure relief valve 85. If desirable steam may be introduced through the pipe 86 in which is interposed a valve 87. The introduction of steam with certain hydrocarbons has the effect, as is well known in the art, of improving the quality of the distillate.

70 In a like manner when the column 46 has been cut into the system and the column 47 cut out, the heated gases are directed to the latter column through an injector pipe 86' similar to that shown at 75 connected and to the header 72. The vaporous hydrocarbons driven from the column 47 pass through the line 87' controlled by a valve 88 to the line 79 and thence through the condensing apparatus explained in connection with the column 46.

80 Thus the apparatus may be operated continuously and if necessary any number of saturating columns may be connected up with the system. It is a well known fact that in cracking hydrocarbon oil there is a large portion of light hydrocarbon fractions which are lost with the incondensable gases and by separately treating the gases in this manner 90 a substantial portion of these hydrocarbon fractions may be extracted.

85 By treating midcontinent gas oil of approximately 32° Baumé gravity to temperatures ranging from 700 to 1000° F. and under pressures ranging from 50 to 500 pounds a yield of good quality distillate may be obtained comprising from 50 to 75% of the oil charged. In connection with this conversation a large volume of incondensable gas is formed from 95 which may be extracted a light distillate having gravities upward of 55 Baumé gravity.

100 I claim:

1. A process for cracking oil consisting in heating the oil to a conversion temperature in a heating zone, passing the oil to a conversion stage and there maintaining it in a substantial body, dephlegmating and condensing the evolved vapors and passing the uncondensed gases through an adsorbent substance, thereby adsorbing any vapors entrained by the uncondensed gases, driving off the adsorbed products by treating the adsorbent substance with heated gases of combustion from the heating zone so regulated as to relieve said substance of said products and condensing and collecting the products thus driven off.

110 2. A process for simultaneously cracking oil and recovering gasoline-like constituents from the uncondensed gases produced as a result of the cracking operation, consisting in subjecting the oil to cracking conditions of 115 temperature and pressure, in dephlegmating the evolved vapors, in subjecting the dephleg- 120

125

130

mated vapors to condensation, in passing the uncondensed gases through a body of adsorb-
ent substance, to adsorb gasoline-like constit-
uents entrained by the uncondensed gases, in
5 recovering the adsorbed gasoline-like constit-
uents from the adsorbent substance, by dis-
continuing the admission of uncondensed
gases to such substance and admitting hot
combustion gases from the heating zone of the
10 cracking process thereto, in regulating the ad-
mission of such heated combustion gases, so
as to relieve said adsorbent substance of all
of the adsorbed products, in thereafter con-
densing and collecting the products relieved
15 from the adsorbent substance.

3. A process for simultaneously cracking
oil and recovering gasoline-like constituents
from the uncondensed gases produced as a
result of the cracking operation, consisting in
20 subjecting the oil to cracking conditions of
temperature and pressure, in dephlegmating
the evolved vapors, in subjecting the dephleg-
mated vapors to condensation, in passing the
uncondensed gases through a body of adsorb-
25 ent substance, to adsorb gasoline-like constit-
uents entrained by the uncondensed gases, in
recovering the adsorbed gasoline-like constit-
uents from the adsorbent substance, by dis-
continuing the admission of uncondensed
30 gases to such substance and admitting hot
combustion gases from the heating zone of the
cracking process thereto, in regulating the
admission of such heated combustion gases, so
as to relieve said adsorbent substance of all
35 of the adsorbed products, in thereafter con-
densing and collecting the products relieved
from the adsorbent substance, and in main-
taining a superatmospheric pressure upon the
uncondensed gases passed through such ad-
40 sorbent substance.

4. A process for simultaneously cracking
oil and recovering gasoline-like constituents
from the uncondensed gases produced as a re-
sult of the cracking operation, consisting in
45 subjecting the oil to cracking conditions of
temperature and pressure, in dephlegmating
the evolved vapors, in subjecting the dephleg-
mated vapors to condensation, in passing the
uncondensed gases through a body of adsorb-
50 ent substance, to absorb gasoline-like constit-
uents from the adsorbent substance, by dis-
continuing the admission of uncondensed
gases to such substance and raising the tem-
perature of the body of adsorbent material to
55 relieve said adsorbent substance of all ab-
sorbed products by waste heat from the heat-
ing zone of the cracking process, and con-
densing and collecting the products relieved
from the adsorbent substance.
